UNITED STATES PATENT OFFICE.

THEODORE C. WHEATON, OF MILLVILLE, NEW JERSEY.

DESIGN FOR A BOTTLE.

45,826.

Specification for Design.

Patented May 19, 1914.

Application filed February 27, 1914. Serial No. 821,586. Term of patent 7 years.

To all whom it may concern:

Be it known that I, THEODORE C. WHEATON, a citizen of the United States, residing at Millville, in the county of Cumberland and State of New Jersey, have invented a new, original, and ornamental Design for a Bottle, of which the following is a specification, reference being had to the accompanying drawing, forming part thereof.

In the drawing:—Figure 1 is a side elevation of the bottle illustrating my design.

Fig. 2 is an edge elevation of the same. Fig. 3 is a transverse sectional view of the same.

I claim:—

The ornamental design for a bottle, as shown.

THEODORE C. WHEATON.
